UNITED STATES PATENT OFFICE.

CHARLES A. FORD, OF NEWARK, NEW JERSEY, ASSIGNOR TO FORD MANUFACTURING COMPANY, A CORPORATION OF NEW JERSEY.

NON-REFILLABLE BOTTLE.

1,140,452.

Specification of Letters Patent.

Patented May 25, 1915.

Application filed June 19, 1913. Serial No. 774,595.

To all whom it may concern:

Be it known that I, CHARLES A. FORD, citizen of the United States, residing at Newark, in the county of Essex and State 5 of New Jersey, have invented certain new and useful Improvements in Non-Refillable Bottles, of which the following is a specification.

The present invention relates to certain 10 new and useful improvements in non-refillable bottles, and has for its object to provide a device of this character which embodies novel features of construction whereby it is impossible to force any liquid into 15 the bottle or container without such breakage of the parts as will clearly indicate that the contents of the bottle have been tampered with, but which will enable the liquid contents of the bottle to be readily 20 poured out of the same in the usual manner.

A further object of the invention is to provide a non-refillable bottle which is peculiarly designed so that the various parts thereof can be cheaply manufactured and 25 easily assembled, which is compact in its construction and does not require any part of the bottle to be made larger than usual, and which admits of the bottles being packed and shipped in the usual manner.

With these and other objects in view, the invention consists in certain novel combinations and arrangements of the parts as will 30 more fully appear as the description proceeds, the novel features thereof being pointed out in the appended claims.

For a full understanding of the invention, reference is to be had to the following description and accompanying drawings, in which:—

Figure 1 is a longitudinal sectional view 40 through a bottle neck provided with a valve construction embodying the present invention, the said view being taken on the line 1—1 of Fig. 2. Fig. 2 is a longitudinal sectional view on the line 2—2 of Fig. 1. Fig. 3 is a transverse sectional view on the line 3—3 of Fig. 1. Fig. 4 is a similar view on the line 4—4 of Fig. 1. Fig. 5 is a sectional view similar to Fig. 1, showing a slight 45 modification of the invention. Fig. 6 is a transverse sectional view on the line 6—6 of Fig. 5. Fig. 7 is a similar view on the line 7—7 of Fig. 5. Fig. 8 is a longitudinal sectional view through the upper end of the 50 bottle neck showing a modified construc- 55

tion of the retaining cap, and Fig. 9 is a similar view showing a still further modified form of the retaining cap.

Corresponding and like parts are referred to in the following description and indicated in all the views of the drawings by the same reference characters.

Specifically describing the embodiment of the invention illustrated by Figs. 1 and 2 of the drawings, the numeral 1 designates the 60 body portion of a bottle or container, and 2 the neck of the same, the said neck being substantially cylindrical in shape and being provided at its outer extremity with the usual bead 3. The neck 2 is contracted 65 at the base thereof to provide a valve seat 4 upon which a ball 5 normally rests by the action of gravity. This ball valve 5 is retained in position and tampering therein effectually prevented by means of a combined cage and baffle A. The member A 70 comprises a pair of separate complementary sections 6 which are similar and interchangeable in construction and are adapted to be assembled from opposite sides and 75 then slipped into the bottle neck over the ball valve 5 so as to provide a baffle and cage for the said valve. Each of the complementary sections 6 of the baffle A has a skeleton construction and is contracted upon 80 the outer face thereof at 6^a and 6^b, the lower contracted portions 6^a of the two sections providing a continuous annular chamber 85 which surrounds the cage 8 within which the ball valve 5 operates, while the upper 90 reduced portions 6^b of the two members 6 provide a continuous annular chamber which communicates with the contracted mouth 18 formed at the upper end of the 95 combined baffle and cage A, and also communicates with the before mentioned annular chamber through the inclined passages 9 provided by the inclined baffle arms or walls 6^c.

The cage 8 is formed by corresponding 100 substantially semi-cylindrical depressions in the lower ends of the complementary members 6, the said depressions providing a cylindrical chamber within which the ball valve 5 is adapted to operate. The inner 105 face of each of the complementary members 6 is provided with a transverse slot 10 and these slots 10 have a greater depth than the semi-cylindrical depressions providing the cage 8 and communicate at intermediate 110

points in their length with longitudinal grooves 11 formed in the sides of the cage and extending throughout the entire length thereof. The extremities of the transverse 5 slots 10 communicate with the lower annular chamber surrounding the valve cage and provide passages through which the liquid within the bottle can enter the lower annular chamber when the bottle is inverted and 10 the ball valve 5 falls away from the valve seat 4.

A transverse abutment or baffle 12 is provided immediately under the contracted mouth 18 of the member A, the said transverse abutment being shown as connected to the top of the valve cage 8 by means of a comparatively thin and transversely disposed web portion 13. The inclined baffle arms 6^c are located upon opposite sides of the web 20 portion 13 and the extremities of the corresponding arms 6^c of the two members 6 abut against each other when the members are assembled within the bottle neck so as to provide a substantially continuous frusto-conical baffle wall between the valve cage 8 and the transverse abutment 12, the said substantially frusto-conical baffle wall being more clearly illustrated by Figs. 1 and 4.

The lower end of the member A is formed 30 with an annular enlargement 6^d which fits accurately within the interior of the bottle neck and is adapted to rest upon the contracted base of the bottle neck. The intermediate portion of the member A is also 35 provided with the annular enlargement 6^e which fits accurately within the interior of the bottle neck, and in a similar manner the outer end of the member A is enlarged at 6^f so as to fit accurately within the interior of 40 the bottle neck. It will thus be obvious that after the two supplemental sections 6 of the baffle member A have been assembled and slipped into the bottle neck, the annularly enlarged portions 6^d, 6^e and 6^f thereof will 45 coöperate with the inner walls of the bottle neck to retain the members 6 in coöperative relation to each other.

The combined cage and baffle member A may be retained in position by means of a 50 cap 15 applied to the extremity of the bottle neck 2. As indicated by Figs. 1 and 2, this cap 15 may be formed of glass and is provided with a central opening corresponding to the mouth 8 of the member A, the 55 said opening being surrounded by an inwardly projecting annular flange 16 which is received within an annular seat 17 formed in the mouth 18 of the baffle A. A suitable washer member 18^a may be arranged in the 60 seat 17 to provide a tight joint between the cap and the baffle member so that there will be no danger of the liquid entering the space between the cap and the end of the bottle neck. The periphery of the cap 15 is 65 rounded by an annular flange 19 which fits

snugly over the exterior of the bottle neck, the edge of the said peripheral flange 19 being adapted to be softened by the application of heat thereto and then turned under the bead 3 of the bottle neck as indicated 70 at 20. The combined cage and baffle member A is then retained securely in position within the bottle neck so that it is impossible to remove the same or tamper with the valve without breaking some of the parts so as to 75 clearly indicate that the bottle has been tampered with.

When the bottle is in an upright position the ball valve 5 rests upon the valve seat 4 so as to prevent entry of any liquid into 80 the bottle. However, when the bottle is inverted the ball 5 will fall away from the valve seat 4 and drop against the opposite end of the cage 8. The liquid within the bottle will then flow through the longitudinal grooves 11 and transverse passages 10 into the lower annular space surrounding the baffle member A, and thence through the inclined passages 9 provided by the frusto-conical baffle 6^c into the upper annular space 85 surrounding the member A, and thence over the transverse abutment or table 12 through the mouth 18. As soon as the bottle is again tilted back into an upright position the ball 5 will drop back upon the valve seat 4 and 90 all efforts to tamper with the same by means of a wire or the like will be unavailing, since the transverse table or abutment 12 coöperates with the frusto-conical baffle 6^c to provide a circuitous path between the mouth 95 100 and the cage 8.

A slight modification is shown in Fig. 5 in which the baffle members 6^g are substituted for the baffle members 6^c. These baffle members 6^g are formed with upper and lower inclined faces which converge inwardly away from the walls of the bottle neck and have a spaced and opposed relation to the web 13 which connects the transverse table or abutment 12 and the upper 110 edge of the cage 8. The construction is otherwise substantially the same, and the operation and manner of assembling the parts identical.

The retaining cap 21 shown by Fig. 5 115 is preferably formed of glass and has a central opening arranged opposite the mouth 18 of the baffle member and surrounded by an outwardly projecting nipple 22. The outer periphery of the cap 21 is formed with the flange 23 which fits over the exterior of the outer end of the bottle neck and has the edge thereof softened by the application of heat thereto and bent inwardly under the bead 3 of the bottle neck as indicated at 120 24 so as to retain the cap in position.

A further modification of retaining cap 125 is shown by Fig. 8, in which a glass cap 25 is fitted against the end of the bottle neck so as to hold the baffle members in position 130

therein, the said glass cap being in turn held in position by means of a metallic ring 26. This metallic ring is formed with an annular flange 27 which fits around the exterior 5 of the mouth of the bottle neck and is adapted to have the edge thereof crimped under the bead 3 of the bottle neck so as to retain the parts in position.

A still further modification of retaining 10 cap is shown by Fig. 9, in which the numeral 29 indicates a cap similar to the cap 15 of Fig. 1, with the exception that the edge of the inwardly projecting flange 30 surrounding the central opening thereof is provided 15 with a tongue 31 adapted to coöperate with a corresponding depression in the seat 32 at the mouth 18 of the baffle members to lock the said baffle members against rotation about their longitudinal axes. As in the 20 previous instance, a washer member 33 may be interposed between the base of the seat 32 and the edge of the flange 30 so as to provide a tight joint between the said members, although this washer is not entirely necessary and may be eliminated if desired. 25

In using the non-refillable bottle, the bottle or container is designed to be first filled in the usual manner. The ball valve 5 is next dropped upon the valve seat 4 and two of the 30 complementary baffle members 6 then properly assembled and slipped into the bottle neck, the said members serving as has been previously described to provide a cage for the ball valve and also to provide baffle members which will effectively prevent tampering 35 with the valve. After the baffle members have been inserted in position, the retaining cap is applied to the extremity of the bottle neck and permanently secured in position, 40 either by crimping the edges thereof around the bead 3 of the bottle neck, or by using a separate metallic ring and crimping the edges of the ring around the base of the bead of the bottle neck. This cap can not be removed 45 without either breaking some of the parts or leaving marks which would clearly indicate that the bottle has been tampered with, and the usual stopper may be inserted in the opening of the cap when the bottle is 50 not in use. With the inwardly projecting flange construction shown by Figs. 1, 2 and 9, the stopper is prevented from projecting an objectionable distance beyond the bottle neck and a compact construction thereby 55 obtained.

Having thus described the invention, what I claim as new and desire to secure by Letters Patent, is:—

1. A non-refillable bottle including a bottle neck having a contracted portion forming a valve seat, a valve resting upon the valve seat, a substantially cylindrical cage member slipped into the bottle neck over the

valve and divided longitudinally to provide complementary semi-cylindrical sections 65 adapted to be assembled from opposite sides, the said sections being provided at the lower ends thereof with corresponding depressions to provide a cage for the reception of the valve, longitudinal grooves being provided 70 at the sides of the said depressions, and transverse grooves being formed in the meeting faces of the semi-cylindrical sections, said transverse grooves coöperating with each other to provide transverse outlet passages 75 leading from the cage and communicating with the longitudinal grooves, and means for retaining the cage member in position.

2. A non-refillable bottle including a bottle neck formed with a contracted portion providing a valve seat, a valve resting upon the valve seat, a cage member slipped into the bottle neck and divided longitudinally to provide complementary semi-cylindrical skeleton sections, said skeleton sections being formed at intervals with exterior annular enlargements engaging the interior of the bottle neck to hold the sections in operative position, the lower ends of the skeleton sections being formed with corresponding depressions to provide a cage for the valve, while the upper portions of the skeleton sections are formed upon their opposed faces with corresponding sinuous grooves adapted 95 to provide sinuous passages connecting the annular chambers provided by the before mentioned exterior annular enlargements upon the interior of the bottle neck. 100

3. A non-refillable bottle including a bottle neck formed with a contracted portion providing a valve seat, a ball resting upon the valve seat, a skeleton cage slipped into the bottle neck and divided longitudinally to provide complementary semi-cylindrical sections adapted to be assembled from opposite sides thereof, the said cage being formed upon the exterior thereof with a series of annular enlargements engaging the interior of the bottle neck to hold the sections in operative position, and the base of the cage member being formed with a valve receiving chamber and transverse outlet passages leading from the valve chamber, a transverse abutment being formed opposite the mouth 110 of the cage and the body of the cage being contracted under the abutment and provided with a substantially frusto-conical baffle, and means for retaining the cage member in position. 115

In testimony whereof I affix my signature in presence of two witnesses.

CHARLES A. FORD.
